UNITED STATES PATENT OFFICE.

JAMES BARKER, OF DETROIT, MICHIGAN, ASSIGNOR TO CHARLES F. BACKUS, OF DETROIT, MICHIGAN.

LEDGER.

SPECIFICATION forming part of Letters Patent No. 777,931, dated December 20, 1904.

Application filed June 17, 1902. Serial No. 112,016.

To all whom it may concern:

Be it known that I, JAMES BARKER, a citizen of the United States, residing at Detroit, in the county of Wayne and State of Michigan, have invented certain new and useful Improvements in Ledgers, of which the following is a specification, reference being had therein to the accompanying drawings.

The invention relates generally to loose-leaf ledgers, and particularly to a back therefor; and it consists in the novel construction of the back and in the peculiar arrangement and combination of the cover-operating mechanism housed therein.

The invention further consists in other details of construction, as will be fully herein-after set forth.

In the drawings, Figure 1 is a cross-section through a ledger embodying my invention. Fig. 2 is a section on line xx , Fig. 1; and Fig. 3 is a perspective view of the back of the ledger, the parts being detached and some shown in section.

The back referred to consists of two complementary inclosing sections C and D, adapted to slide one within the other in the manner hereinafter set forth. Each section, as shown, is made from a single strip of sheet metal bent to form a back member E, sides F, and a cover portion G. An oblong metallic plate H is riveted to the under side of each of the cover portions, which are cut away at their ends, as shown, to allow flanged portions f' of the side members F to be riveted directly to the plates H, thereby forming smooth and even surfaces for the section-tops.

I represents guide-flanges upon one of the sections, as D, which receive the sides of the complementary member and permit of vertical movement of the sections in relation to each other. Each section also carries secured to its plate H post members A', which are adapted to telescope when the sections are in operative relation to each other. The covers K of the ledger are provided with the usual clamping-plates L, hinged thereto, and these plates are in turn secured, by means of screws a and nuts b, to the cover-tops.

Journalized within bearings c, preferably

upon the lower complementary section of the back, is a shaft M, having right and left hand screw-threads formed thereon upon opposite sides of the central bearing d. The shaft is further provided with a square end e, which projects through an opening f, formed in the section side. The shaft M is swiveled within the bearings and is held against endwise movement by means of suitable shoulders h and a nut i, which engages one of the end bearings, as shown.

O designate nuts upon the shaft, one engaging each thread, as shown, and P are rigid links pivoted at their lower ends to ears j upon the nuts and at their opposite ends to lugs k, depending from the section C.

Q designates stops in the form of screws secured to the plate H upon the lower inclosing section adapted to limit the inward movement of the nuts.

In operation, the parts being as shown in the position illustrated in Fig. 1, the covers are separated by rotating the shaft in a direction to cause the nuts to travel to the shaft ends, the shaft being actuated by a suitable key. (Not shown.) The ledger-leaves may then be inserted or removed from between the covers and the latter returned to their initial position by the rotation of the shaft in the opposite direction.

From the description of my invention it will be seen that the back described constitutes a housing for the operating mechanism, by means of which the covers are drawn together or separated, and on account of the simple construction of the complementary sections a rigid and durable structure is produced at a minimum cost.

What I claim as my invention is—

1. In a loose-leaf ledger, a ledger-back having two complementary inclosing sections, each section having a top and ends with inwardly-turned flanges, the inner and outer surfaces of said flanges being flush with the inner and outer surface of the top of the sections, and slidable connections between the sections.

2. In a loose-leaf ledger, the combination with a ledger-back comprising two comple-

mentary vertically - movable inclosing sections, each section having a top and ends with inwardly-turned flanges, the inner and outer surfaces of which being flush with the inner and outer surface of the top of the sections, telescoping posts between said sections, a shaft swiveled in bearings upon the inner surface of one of the sections and provided with a right and left hand screw-thread, nuts engaging the thread and rigid links pivoted to the nuts and to the complementary section.

3. In a loose-leaf ledger, the combination with a ledger-back comprising two complementary vertically-movable sections, of a plate secured to the under surface of the top of one of the sections, which top is cut away at its ends, end sections having inwardly-turned flanges closely fitting the cut-away portion of the top and engaging the plate for forming a

smooth connection with the top section, and 20 telescoping posts between the sections.

4. In a loose-leaf ledger, the combination with a ledger-back comprising two complementary vertically-movable sections, of a plate secured to the under surface of the top of one 25 of the sections, which top is cut away at its ends, end sections having inwardly-turned flanges closely fitting the cut-away portion and engaging the plate, telescoping posts between the sections, means for adjusting the 30 cover-sections, and means for limiting the inward movement of the sections.

In testimony whereof I affix my signature in presence of two witnesses.

JAMES BARKER.
